NETHER GARMENT

Shoichi Nishimoto, Los Angeles, Calif.

Application April 8, 1929, Serial No. 353,326

4 Claims. (Cl. 2—224)

This invention relates to that class of nether garments provided with over-lapping front flaps for the purpose of affording double protection of warmth to the abdomen.

5 A feature of this invention is the construction and arrangement of a belt in combination with the back of the garment and the front flaps thereof to give additional support and warmth without uncomfortable or injurious restriction of the 10 bowels of the wearer and with an appropriate supporting of the abdomen.

An object of the invention is to provide a female garment adapted to support the abdomen during pregnancy without uncomfortable or injurious 15 restriction.

A further object is to make provision for producing the garment at a minimum expense of material, and to allow freedom for toilet purposes at front and back of the wearer.

20 A feature of the invention is improved side extensions that are adapted to overlap each other at the front of the garment, and the provision of snap fasteners in such positions that they insure easy and ready attachment and detachment for 25 the purpose of securing the garment on the person and removing it from the person without any likelihood that the attachment may become loosened so as to allow the garment to fall.

The garment is adaptable for both masculine 30 and feminine wear; and is shown herein with a crotch strap adapted to provide a menstrual pad support and adapted for omission or application as occasion may require.

I also provide convenient and firm attachment 35 means for supporting the stockings for female wear.

Other objects, advantages and features of invention may appear from the accompanying drawings, the subjoined detailed description and 40 the appended claims.

The garment may be made of various suitable materials and may be of various sizes, shapes and proportions.

The accompanying drawings illustrate the invention in a form at present deemed preferable, but I do not confine the invention to the particular construction shown, as the same may be varied within the judgment of the manufacturer without departing from the spirit of the invention.

45 Figure 1 is a fragmental perspective front view of the garment as the same would appear on the person of the wearer; the crotch strap being unfastened at the front and lowered to expose construction that would otherwise be hidden.

50 Fig. 2 is a view of the top and inner face of the

crotch strap detached, with front end up and rear end down.

Fig. 3 is a rear view of the garment closed, without the crotch strap, and with the belt unfastened; 60 dot and dash lines across and at the left side of the view, indicate the position of the belt after it has been brought across the back, and before its free end has been carried around in front of the person of the wearer, not shown.

Fig. 4 is a fragmental rear view of the garment 65 spread out, a portion of the belt being broken away to contract the view; the crotch strap being omitted.

Fig. 5 is a view showing patterns or pieces by 70 which the garment may be made.

The combined body and leg piece *a* may be of any suitable fabric or material and in outline has the waist line top edge 1, the mid line back edge 2, the rear arcuate toilet notch edge 3, the inner front leg seam edge 4, the arcuate bottom leg edge 75 5, the outer front leg seam edge 6, the front toilet notch edge 7; the front flap edge 8 and the side flap end edge 9, and is provided at 10 and 11 with darts to give curvature to the waist band 12 which comprises a strip *b* of strong material folded over 80 at the edges and stitched to the top edges 1 of the body and leg pieces *a*, *a'*, that go to make up the garment. It is understood that the belt reinforcement 13 may be of one piece, but it is shown made up of four pieces, *c*, *c'*, *d*, and *d'*, fastened 85 together and fastened to the upper parts of the body and leg pieces. The free end 14 of the belt is shown made up of the pieces *e* and *f* fastened together at *g* and to the ends of the belt reinforcement at *h*. 90

15 and 15' are front flaps formed of side extensions of the back and are constructed to overlap and thus to form two plies in front of the abdomen. The ends of the over-lapping front extensions or flaps 15 and 15' are practically at right 95 angles to the top edge 1 of the garment and are reinforced by end pieces 16 formed of the pieces *i* of the pattern, stitched in place. 17 is the buckle strap formed of the pattern piece *j*, appropriately folded over at its edges and passed through 100 the loop 18 of the buckle 19, and fixed to the end of the over-lapping flap 15.

The back pieces *c*, *c'*, are broadened at their meeting ends as at 20 and are narrowed to the 105 width of the strips *d* to which they are secured.

The stocking supporter straps 21 are fixed to reinforcements 21' on the inside of the body from the lower edge of the belt reinforcement to the point at which the supporter straps are at- 110

tached and hang down inside the leg and are provided with the fasteners 23.

When the parts are assembled the toilet notches at 7 of the united body and leg pieces form at the front, a front toilet opening 24 and the rear toilet notches 3 form at the rear, the toilet opening 25.

Provision is made whereby the free ends of the flaps are detachably fastened to the front.

- 10 The flap member 15 is provided at its end on the outer face with snap fastener members 26, and the body member *a*' is provided on its inner face with snap members 26', complementary to the snap members 26 so that when the flap is closed over the abdomen of the wearer, the snap members 26 and 26' may be engaged with each other to hold such flap member in place; and the flap member 15' is provided on its inner face with snap fastener members 27 to engage complementary snap fastener members 27' on the outer side of the body member *a* so that when the flaps 15 and 15' are in place, the flap 15' will overlap the flap 15 and both flaps will be securely connected to the body, and the belt may be brought around the body portion and the free end of the belt may be secured by the buckle 19.

The crotch strap 28 has expanded front and rear ends 29, 30. The front end 29 has snap fasteners 31 to engage complementary fasteners 32 on the outside of the flap 15', and the expanded end 30 is provided with snap fasteners 33 complementary to the snap fasteners 34 that are secured to the outside of the body at the lower edges of the belt reinforcement *c*, *c*'.

35 The curved lower edges 8 of the flaps extend as a single line of beauty which extends along the upper edges of the adjacent portion of the legs and around the margins of the notch openings at 24 so that when the garment is in place, the front toilet opening 24 is provided for; and when the crotch strap is secured in place, both front and rear toilet openings 24 and 25 are covered thereby.

By loosening the snap fasteners 31, the crotch strap may be swung down, back and away from the body and legs of the garment thus leaving the toilet openings 24 and 25 unobstructed; or vice versa, the rear end of the crotch strap may be unfastened and the strap brought down and forward to leave the toilet openings free.

50 It is thus seen that the garment comprises a body portion extending from the waist line top edge 1 as a back piece to near the rear toilet opening 25, the short leg portion below such opening and the intermediate portion containing such toilet opening; and that the forward flaps terminate in parallel edges at the body portion of the garment and overlap and are secured together by readily released devices as the snap fasteners and that there is a continuous edge extending 60 from the lower ends of the parallel edges to form the tops of the inner sections of the legs and the front and rear toilet openings 24, 25.

I claim:

65 1. A nether garment having a back provided with a rear toilet opening and a front, having a

front toilet opening and having front flap extensions, the upper edges of which are aligned with the upper edge of the back; said extensions terminating in edges substantially vertical to the plane of the top edges of the back and flaps; the under edges of said flaps being continuous with the edges of said toilet openings; and a belt fixed to the flaps and the back of the garment and adapted to over-lap at the front of the garment below the top edges of the body and flaps of the garment; and means to secure the over-lapping end of the belt to the end of the over-lapping flap.

2. A nether garment having legs and a back, and having at the crotch, a notch extending up into the back and forming a rear toilet opening, and a front, having a front toilet opening; said garment also having front flap extensions, the top edges of said extensions being aligned with the top edge of the back, the ends of such extensions being at right angles to such top edges and the under edges of said extensions being upwardly oblique continuations of the margin of the toilet openings; said flaps being adapted and arranged to overlap each other and to cover the front of the wearer below the waist line; fastening means to connect the free ends of said flaps respectively to the front; a belt extension fastened to the end of one of said flaps and having a free end and adapted to extend around the garment above the toilet openings and securement means for the free end of said belt extension.

3. A nether garment having legs and a back, and having a notch at the crotch extending up into the back and forming a rear toilet opening and a front, having a front toilet opening; said garment also having front flap extensions, the under-edges of said extensions being upwardly oblique continuations of the margins of the edges of the front and rear openings; said flaps being adapted and arranged to overlap each other and to cover the front of the wearer below the waist line; fastening means to connect the free ends of said flaps to the front; a belt extension fastened to the end of one of said flaps and adapted to extend around the garment above the notch, and securement means for the free end of said belt extension; snap fastener members fixed to the belt near the lower edge thereof at front and back; a crotch strap having a narrow neck to extend through the notch and having expanded ends; and snap fastener members at the ends of the crotch strap to engage the fixed snap fastener members on said belt at front and back.

4. A nether garment comprising legs, a back, a front and front flap extensions; said back being provided with a rear toilet opening; said front being provided with a front toilet opening; a belt fixed to the flaps and the back of the garment and provided with an intermediate buckle; said belt being of such length beyond the buckle that it can be brought around the back of the garment and flaps and passed through the buckle.

SHOICHI NISHIMOTO.
